UNITED STATES PATENT OFFICE.

JOHN MACKAY, OF AUDUBON, NEW JERSEY, ASSIGNOR TO THOMAS SAVILL'S SONS, OF PHILADELPHIA, PENNSYLVANIA.

DESIGN FOR A FAUCET FOR A COFFEE URN OR SIMILAR ARTICLE.

Application filed November 4, 1924. Serial No. 11,292. Term of patent 14 years.

To all whom it may concern:

Be it known that I, JOHN MACKAY, a subject of the King of Great Britain, having declared my intention of becoming a citizen of the United States, residing at Audubon, in the county of Camden and State of New Jersey, have invented a new, original, and ornamental Design for Faucet for Coffee Urn, or Similar Article, of which the following is a specification, reference being had to the accompanying drawing, forming a part thereof.

The figure is a perspective view of a faucet adapted for use with coffee urns or like dispensing devices, showing my new design.

I claim:

The ornamental design for a faucet for a coffee urn or similar article, as shown.

JOHN MACKAY.
